(57) **CLAIM**

The ornamental design for a shoe insert, as shown and described.

DESCRIPTION

FIG. 1 is a bottom, side perspective view of a shoe insert showing my new design;

FIG. 2 is a bottom plan view thereof;

FIG. 3 is a top plan view thereof;

FIG. 4 is a side elevation view thereof;

FIG. 5 is the opposite side elevation view thereof;

FIG. 6 is a front elevation view thereof; and,

FIG. 7 is a rear elevation view thereof.

The broken lines depicting portions of the shoe insert are for the purpose of illustrating portions of the shoe insert that form no part of the claimed design.

1 Claim, 5 Drawing Sheets
